(57) CLAIM

The compact disc (CD)/box opener having an appearance of a CD case, as shown and described.

DESCRIPTION

FIG. 1 is an elevated perspective view of the compact disc (CD)/box opener having an appearance of a CD case showing my new design;

FIG. 2 is a rear view of the compact disc (CD)/box opener having an appearance of a CD case;

FIG. 3 is a side view of the compact disc (CD)/box opener having an appearance of a CD case;

FIG. 4 is a front view of the compact disc (CD)/box opener having an appearance of a CD case;

FIG. 5 is a top view of the compact disc (CD)/box opener having an appearance of a CD case; and,

FIG. 6 is a bottom view of the compact disc (CD)/box opener having an appearance of a CD case.

The broken line showings of the internal structure are for illustrative purposes only and form no part of the claimed design.
